TELEVISION RECEIVER

August Karolus, Leipzig, Germany, assignor to
Telefunken Gesellschaft für Drahtlose Tele-
graphie m. b. H., Berlin, Germany, a corpora-
tion of Germany

Application May 1, 1937, Serial No. 140,152
In Germany May 6, 1936

4 Claims. (Cl. 178—7.3)

In order to receive television images on a projection screen, whereby said images are transmitted on a channel, in other words for the reconstruction of television images in the receiver, attempts have been made to project the image of the fluorescent screen of a Braun tube. In fact, this suggestion permits of producing with comparatively satisfactory brightness, images whose size is below 1 m.², but serious difficulties are encountered when attempting projection of television receiving images on a screen surface of the size of about that of a movie screen, i. e., on a surface of about 10 m.². To this end it would be necessary—even when assuming that the fluorescent mass would be such as to supply the required luminous currents—to increase the voltage as well as the current amperage of the cathode ray to values that make their control entirely impossible. Furthermore, at such a high voltage the X-rays released by the cathode ray impingement in the fluorescent mass would cause a very great disturbance. In present day Braun tubes for projection purposes the voltage values of about 15 kv., and current values of about 3 ma. in use produce inconvenient effects. In fact a uniform brightening-up of the entire fluorescent screen is hereby produced which can be explained only through the appearance of X-rays. Even at a voltage of 15 kv., and a cathode ray current of 3 ma. only a current of light is obtained on the screen surface that is 200 to 400 times smaller than the luminous current on an ordinary movie screen.

In order to overcome these difficulties, in accordance with the invention a multiplicity of cathode ray systems comprising fluorescent screens are so to say placed in parallel, so that each cathode ray system is permitted to bombard its fluorescent screen during a time that is longer than that available for transmitting the respective image element. In this case, the current in the individual cathode ray systems can be controlled by means of a cathode ray switch in which each contact element assigned to one cathode ray system is engaged by the switching cathode ray only for about the length of time in which the respective brightness value to be imparted to the image element is televised. The switch sets each cathode ray system so that therein an electron bombardment of the fluorescent screen occurs even after the switching ray has again moved away from the contact element. Hence, the luminous currents coming from the individual fluorescent screens impinge on the screen surface at a very considerable time overlapping.

The invention therefore resides in the combination of a cathode ray switch and a multiplicity of parallel connected cathode ray systems each having a fluorescent screen, each of which

after the setting by the cathode ray switch, irradiates its fluorescent screen during a longer time than that in which the switching cathode ray remains on the appertaining contact element.

Several embodiments of the invention are described in the following and schematically represented in the drawings, in which

Fig. 1 is an embodiment of my invention,

Fig. 2 is another embodiment of my invention,

Fig. 3 is an explanatory diagram,

Fig. 4 is an explanatory curve,

Fig. 5 is a further embodiment of my invention,

Fig. 6 shows an arrangement of cathode ray systems, and

Figs. 7, 8, 9 are particular constructions of the cathode ray tube.

In Fig. 1, 1 designates a glass bulb containing a cathode 11, a control organ 12 such as for instance a Wehnelt cylinder, and an anode 13, as well as a multiplicity of contacts 14 through 17 being illustrated, provided with separate lead-ins. The anode 13 is maintained at a positive potential relative to the cathode by means of a direct potential source 18. The contacts 14 are connected to the grounded positive pole of the potential source 18 across a respective RC-element 19 and a common direct potential source 22, this connection line also containing a potential source 22 having its positive terminal joined to the RC-elements. Each of the contacts 14, etc., is also connected to the control organ of a cathode ray system comprising a fluorescent screen, shown in Fig. 1 schematically only, by a triode 23 with a direct potential source 24 inserted in its cathode lead-in. The term RC-element used herein means a resistance-capacity circuit or time constant circuit.

To explain the functioning of the arrangement according to Fig. 1, it is assumed that across the control electrode 12 designated by the term "image" there will be applied either the high or intermediate frequency potential modulated with the image content, or the voltage supplied by a detector circuit. The cathode ray of the switch thus varies its intensity in accordance with the pattern of the image brilliancy and is caused to sweep over the contacts 14, 15, 16, etc., arranged along a line, or along a circle, said sweeping being obtained by means of a saw-tooth shaped deviation field, or by means of a rotary field. This ray may remain on each of the contacts as long as the brightness of an image point is transmitted. Viewed in the direction of the electron passage, the ray current then passes from the cathode to the one of the contacts 14, 15, 16, etc., through one of the condensers of the RC-members 19, 20, 21, etc., across the potential source 22 and 18, and back to the

cathode 11. The part of the ray current returning eventually directly from the anode 13 to the cathode 11 does not require consideration. The condensers receive thereby a charge Q 5 corresponding to the incidental value i_p of the ray current, multiplied by the duration of an image point BPD.

$$Q = i_p \cdot BPD$$

10 This charge furnishes at the condensers a voltage E determined by the quotient formed by the charge and the capacity C .

$$E = Q/C$$

15 Since the ray current i_p varies, the voltages applied to the individual condensers differ likewise. During the time elapsing until the cathode ray returns upon the respective contact element, the condenser potentials dissipate themselves across the parallel connected resistors, thus prevailing 20 for a considerably longer time although the value thereof decreases, than the time in which the cathode ray touches the appertaining contact element, i. e., during a time which is much longer than the duration of the image point BPD. 25 Since the voltage is built up at the individual condensers with the speed of succession of the individual image points, there is always a multiplicity of condensers effective at the same time, i. e., the cathode ray systems comprising fluorescent screen are so-to-say connected in parallel, since the operating periods thereof extending throughout the entire discharge period of the condensers, overlap each other.

30 Another mode of construction for the cathode ray switch is shown in Fig. 2, and differs from that of Fig. 1 in that in addition a second anode 25 is provided, maintained relative to the anode 13 at a positive potential by the potential furnished by the direct voltage source 26, and serving 40 for further acceleration of the cathode ray beam and also for its concentration. Otherwise, the functioning of the arrangement according to Fig. 2 is the same as that described on hand of Fig. 1.

35 Instead of having the condensers of the RC-members 19, 20, 21, etc., charged by the ray current as explained in connection with the Figs. 1 and 2, it is possible in changing the poles of the direct potential source 22 to utilize the secondary electrons appearing on the contact 14, 15, 16, etc., 50 for charging the condensers.

To explain this mode of operation, the known phenomena of secondary emission will again be briefly reviewed in connection with Figs. 3 and 4. In Fig. 3, the reference characters 11 to 13 and 55 18 designate the same means as in Fig. 1. An absorption plate 14' which is capable of secondary emission is connected by direct contact with the anode 13 across the direct voltage source U having the poles reversed as compared with the direct voltage source 22 shown in Fig. 1. Items i_p , i_s , i_d designate three current meters placed in the cathode lead-in, in the lead-in for the anode and in the lead-in for the absorption plate 14'. At a certain ray amperage i_p there is observed the current pattern designated by i_s in Fig. 4 in relation to the voltage U whose polarity indicated in Fig. 3 corresponds to the positive abscissa axis in Fig. 4, and for a higher amperage of the ray i_p the pattern designated by i_s is observed. As long as the 70 voltage U is negative, i. e., as long as the latter has the same polarity as the voltage source 22 in Fig. 1, a current flows only through the circuit indicated by the dotted line L, said current when viewed in the direction of the electron movement 75 has the direction indicated by the arrows. The

absorption plate 14' has positive potential relative to the anode 13, and consequently, secondary electrons produced on this absorption plate cannot leave this plate. This condition corresponds with points of the curve situated to the left of the 5 ordinate axis in Fig. 4. The current measured in the meter i_d hence, is equal to the current i_p while the current i_s equals zero. However, if the voltage U has a considerable value (for instance higher than 15 volts) and if it has the polarity 10 indicated in Fig. 3, there appears in the circuit M in addition to the ray current (in circuit L) the secondary emission current of the plate 14'. This current has the direction indicated by arrows when viewed in the direction of the electron 15 movement. The secondary electrons thus pass from the absorption plate 14' to the anode 13, being therefore a secondary emission anode, said electrons passing furthermore through the meter i_s , through the voltage source U , then meter i_d 20 and back to the plate 14'. When the surface of the plate 14' is provided with a suitable material, this secondary emission current can be a multiple of the current i_p . In the meter i_d in which the currents have opposite directions, there 25 can thus only be observed the difference i_d between the secondary emission current i_s that can be fully measured in the instrument i_s , and the ray current i_p . This condition has the corresponding curve points situated on the horizontal 30 curve parts to the right of the ordinate axis in Fig. 4.

In order to operate on these curve branches, it is therefore only necessary to reverse the polarity 35 of the voltage source in Figs. 1 and 2, so that the negative pole of said source lies towards the RC-members 19, etc. As regards value, the current i_d charging the condensers of the RC-members is larger than the current i_p as soon as the secondary emission factor SEF is higher than 2 40 on the plate 14'. Hence, the charge which the condensers receive while the image point endures is:

$$Q = i_p (SEF - 1) BPD$$

45 As before, the voltage of the condensers is again determined from the quotient of the charge and capacity.

In utilizing the secondary emission phenomena at the contacts of the cathode ray switches the condenser charges can thus be increased, and 50 hence a more intensive control of the cathode ray systems equipped with fluorescent screen can be carried out.

A still further mode of operation of the new arrangement can however also be explained by 55 reference to Fig. 4. When operating with a non-varying ray current i_p , i. e., if the potential of the control electrode 12 relative to the cathode 11 is maintained invariable, the curve i_s or i_d in Fig. 4 is correct as already explained. If the voltage U in Fig. 3 is shown with the same polarity as in Fig. 3, but its value chosen low as compared with the case previously explained, namely for instance equal to e_1 , e_2 in Fig. 4, the indicated working points of the curve i_s can be controlled in 60 the steep, and approximately straight region when connecting for instance, the image voltage varying with the brightness of the image point, between the voltage source 22 (whose negative pole must now be turned towards the RC-members) and the RC-members. Thus, also in this way a charge which varies in accordance with the respective brightness of the image point, can be supplied to each of the condensers in the RC-members. The steep curve branches in Fig. 4 70 75 80 85 90 95 98

correspond to an operating state in which the secondary emission current will be influenced in the same manner by the space charge of the secondary emission (in front of the plate 14') as is the case in an ordinary amplifier tube as regards the electron current in the so-called Langmuir space charge region.

Hence three different operating possibilities are available:

10 1. The condensers are charged only by the primary current. The potentials of the contacts 14, etc., are positive relative to the anode 13. The secondary electrons cannot leave the contacts (horizontal left hand curve branch in 15 Fig. 4).

2. The condensers are charged by the saturation current of the secondary emission. The potentials of the contacts 14, etc., have a negative value relative to the anode 13 that is higher 20 than about 15 volts, said anode being now at the same time the anode for the secondary emission path 14'-13. The secondary emission factor of the contacts 14, etc., must be greater than 2, if the condenser charges hereby obtained are to be 25 higher than in case 1 (horizontal right hand curve branch in Fig. 4).

3. The contacts 14 are rendered but slightly negative relative to the secondary emission anode, and the space charge current of the secondary 30 emission is used for charging the condensers (steep curve branch in Fig. 4).

Principally, the arrangements of the type described can be obtained by assigning to each 35 image element of the entire television image, a cathode ray system comprising fluorescent screen. The time constant of the RC-members is then so dimensioned that each condenser will practically be discharged during the time for the entire image. The entire screen surface will then be 40 reproduced on a projection screen.

An especially simple arrangement will be obtained when using a number of cathode ray systems corresponding to the image elements of the one image coordinate, and a photo-optical arrangement for instance a mirror wheel for the image reconstruction in the other image coordinate, and at the same time for the reproduction 45 on the projection screen. In this way, the number of required switch contacts will be decreased, and on the other hand, it is possible conveniently to accommodate all cathode ray systems within one vacuum vessel, to provide respectively a common potential for their cathodes, or control grids, as well as their anodes, so that 50 the number of the lead-in wires to be insulated from each other will be greatly reduced.

A form of construction for such common vacuum vessel is shown in Fig. 5 of the drawings. Herein, 27 represents a tank-shaped glass 60 vessel with U-shape cross-section on which is glued a possibly plane parallel glass plate 28 by means of a glass enamel having a high melting point. The vacuum vessel contains a copper pipe 29 passed by cooling water, and which carries 65 the fluorescent mass 30. The common anode of all cathode ray systems is designated by 31, a control grid of one system is 32, and a common band-shaped cathode for all systems is designated by 33. The control grids of the individual systems may be advantageously equipped with 70 springs 34 resting against the through-leads 35. The latter suitably consist of a colloidal gold deposit extending from the inside of the vessel up to its outside, and which can be fused into

the said glass enamel binder. The copper tube 29 may have furthermore, a positive potential applied relative to the anode 31, so that after the passing of the cathode rays through the anode 31 a further acceleration takes place. Eventually, the copper tube 29 may also be utilized as a single anode.

Instead of bringing out the control grids 30 separately as shown in Fig. 5, also an indirectly heated cathode may be used, and the carriers of 10 the active cathode material may be brought out separately. In this latter case, all control grids have a common fixed potential applied. The current is then controlled in each cathode ray system in that the individual cathode carriers 15 receive a higher or lower potential relative to the common control grid.

Fig. 6 shows the manner in which the cathode ray systems are symmetrically arranged within the common vacuum vessel. The half of these 20 systems has the axis 36, the other half, the axis 37.

Fig. 7 shows a further mode of construction for the common vacuum vessel, in which the fluorescent screens are provided on a closing-up 25 wall of the vacuum vessel produced of metal and provided with cooling ribs. Instead thereof also a water-cooled closing-up wall composed of glass or of metal according to Figs. 8 and 9 can be used.

The cathode ray switch may also be eventually accommodated together with the cathode ray systems in the same vacuum vessel, as a result of which the total number of necessary insulated lead-in wires can still further be reduced very 35 considerably.

What I claim is:

1. A television receiving apparatus for projection purposes comprising a cathode ray tube having a plurality of target members each representing an elemental area of the image to be reconstructed, means for modulating the cathode ray beam of said tube in accordance with received picture signals, means for directing said beam sequentially on said target members, means for storing a charge in accordance with the value of the beam striking a target member, a plurality of means for reconstructing elemental sections of the optical image, each of said reconstructing means being connected electrically to one of said target members, and means interposed between said image reconstructing means and said target member for maintaining the optical reconstruction of any section of the picture for a time interval proportional to the charge stored by the 55 target member representing that section of the picture.

2. An arrangement in accordance with claim 1 wherein each of said target members has a cathode ray associated therewith, and all of said 60 cathode ray and target member systems are enclosed within a common envelope.

3. An arrangement in accordance with claim 1 wherein the reconstructing device or the elemental sections of the picture is a cathode ray 65 tube having a fluorescent screen, said screen being artificially cooled.

4. An arrangement in accordance with claim 1 wherein a device for reproducing each elemental area of the picture to be reconstructed is a 70 cathode ray tube having a fluorescent screen, said screen being water cooled.

AUGUST KAROLUS.
